UNITED STATES PATENT OFFICE

SAMUEL SEGAL, OF NEW YORK, N. Y., ASSIGNOR TO SEGAL AUTOMATIC TWEEZER CORPORATION, OF NEW YORK, N. Y., A CORPORATION OF NEW YORK

TWEEZERS

Application filed September 27, 1927. Serial No. 222,279.

This invention relates to a tweezer of improved construction and particularly a tweezer by means of which imbedded and foreign particles, as well as hairs, may be 5 grasped and removed with facility.

It is an object of the invention to provide a device of this character, the parts of which will be relatively few in number and rugged and simple in construction. To provide a 10 finished device capable of being sold at a relatively nominal figure and operating over long periods of time with freedom from mechanical difficulty.

It is a further object of the invention to 15 construct a device of this character in which the parts may be assembled or detached from each other with a minimum of effort.

Another object is that of providing a 20 tweezer which will occupy a minimum amount of space when not in use and which, in use, may be manipulated in a desirable manner.

With these and further objects in mind reference is had to the attached sheet of drawings illustrating one practical embodiment 25 of the present invention, in which:

Figure 1 is a side elevation of a tweezer.

Figure 2 is an edge view thereof.

Figure 3 is a view similar to Figure 1, but 30 showing the parts in housed or normal position.

Figure 4 is a fragmentary, partly sectional enlarged view of certain of the elements preferably embodied in the present tweezer, and

Figure 5 is a perspective view of these 35 elements.

In these views the numeral 10 indicates the jaws of the tweezers, the rear ends of which (hereinafter described) are housed within a 40 tube 11, the latter serving as a mounting for the inner ends of a pair of arms 12 which, to this end, are pivotally connected as at 13 to the head 14 of the tube 11.

Swingingly secured to the head at points 45 beyond the pivots 13 is a loop member 15 which is of sufficient size to enclose the arms 12 and the jaws 10 when they have been moved towards each other in the manner shown in Figure 3, this loop serving also as 50 a handle by means of which the tweezer may

be supported while the fingers of the operator are manipulating the arms 12.

With reference to Figures 4 and 5 it will be observed that the head 14 is, in the present instance, formed with a transverse bore serving to accommodate a spring 16 which has its ends extending beyond the bore ends and engaging one with each of the inner faces of the arms 12, thus normally tending to force these elements away from each other to the 55 positions shown in Figures 1 and 2. Furthermore, it will be noted a plug 17 is slidably mounted within the bore of the tube 11 and this plug has its outer end extended to provide, in the present instance, a pair of flat 60 and opposed surfaces 18. The jaws 10, in the present instance, each embrace channel members and their inner ends are of a configuration such that they may enclose the squared 65 portion of the plug, it being noted that their innermost edges, in the present instance, bear 70 against the outer side face of the rounded portion of this element.

Links 19 are interposed one between each 75 of the outer surfaces of the jaws and the arms 12, and by means of a spring 20 arranged within the bore of the tube 11 and between the inner end thereof and the plug 17, the action of the spring 16 will be supplemented 80 to always tend to maintain the parts in the position shown in Figures 1, 2 and 4. At this time it will also be noted that the pivotal 85 connection 13 between the arms 12 and the head 14 of the tube is preferably achieved by the use of headed pins 21, the bodies of 85 which extend through openings in ears 22 formed at the inner ends of arms 12 and bores formed through the head of the tube. As a consequence, under the action of the spring 16, which is constantly tending to move the 90 inner ends of the arms away from each other, the pin heads will overlap the outer surfaces 95 of the ears 22, as has been shown in Figure 4.

Thus, under normal conditions, accidental displacement of the pins is precluded, although these pins afford proper pivots.

However, if for some reason it is desired to gain access to the interior of the tube, this may readily be accomplished by simply gripping the arms 12 adjacent their points of piv- 100

otal connection to the head, which will cause the openings in the ears to align with the bores in the head, whereupon—the bodies of the pins being relieved of any clamping strain—they will fall clear of the ears and the inner ends of the arms may now be moved upwardly and outwardly, permitting the removal of the spring 16, as well as a withdrawal of the inner ends of the jaws 10 from within the tube, together with a removal of the plug and the spring 20 from the latter.

Under normal conditions of operation it will be observed that the ends of the links 19, in the present instance, act as movement 17 limiting members preventing too great a projection of the jaws 10, and also serving, upon a release of the arms 12, to bring the parts to a sufficiently abrupt stop to assure, generally, the expelling of any gripped and removed 23 particle from between the jaws. An operator obviously moves the loop 15 primarily from the position shown in Figure 3 to the position shown in Figures 1 and 2, which results in the remainder of the parts assuming the position shown in these latter figures. Now, using the loop 15 as a handle resting and gripped between the palm and three last fingers of the hand, he is able, by applying the thumb to one of the arms 12 and 30 the index finger to the other arm thereof to manipulate the device with facility, it being obvious that any minor shifting may be achieved by swinging the tweezer with respect to the handle or loop.

Thus it is apparent that, among others, the objects specifically aforementioned are achieved, and it is to be understood that the device may be constructed of any desirable material and that its construction may be 40 modified in numerous particulars without departing from the spirit of the invention, which is defined in the following claims.

I claim:

1. A tweezer including a pair of jaws, a tube within which the inner ends of said jaws extend, a plug within said tube, and the end edges of said jaws extending substantially in line with the bodies thereof and loosely bearing against the side faces of said plug.

2. A tweezer including a pair of jaws, a tube for receiving the inner ends of said jaws, a plug slidably mounted within said tube, a squared portion extending outwardly 55 from said plug, the inner edges of said jaws being substantially in line with the bodies thereof and loosely extending in contact with the side faces of said plug, the squared portion of the latter bearing against the inner faces of said jaws.

3. A tweezer including a pair of jaws, means for mounting the same, a pair of arms connected to said jaws to move the same to gripping position and bodily rearwardly, and

a handle pivotally secured to said mounting means and movable to a position enclosing said arms, and retaining the jaws in rearward position.

4. A tweezer including a pair of jaws, 70 means for mounting the same, a pair of arms connected to said jaws to move the same to gripping position and bodily rearwardly and a loop extending from said mounting means and movable to a position enclosing said arms 75 and retaining the jaws in rearward position.

5. A tweezer including a pair of rockable elements, a mounting member and means for pivotally connecting said elements to said member, said means including a headed pin 80 extending through openings formed in said elements and mounting member, and having its head of less diameter than said openings.

6. A tweezer including a pair of jaws, a tube slidably mounting within its bore the inner ends of said jaws, a pair of arms connected with said jaws to move the same into gripping position and subsequently retract said jaws, said arms being formed with openings and the end of said tube being likewise 90 formed with openings and pins extending through said openings and heads forming a part of said pins and of less diameter than said openings.

7. A tweezer including a pair of jaws, a 95 tube slidably mounting within its bore the inner ends of said jaws, a pair of arms connected with said jaws to move the same into gripping position and subsequently retract said jaws, said arms being formed with openings and the end of said tube being likewise 100 formed with openings, and pins extending through said openings and heads forming a part of said pins and of less diameter than said openings, and means for clamping said pins in position.

8. A tweezer including a pair of jaws, a tube slidably mounting within its bore the inner ends of said jaws, a pair of arms connected with said jaws to move the same, said arms being formed with openings and the end of said tube being likewise formed with openings, and pins extending through said openings and heads forming a part of said pins and of less diameter than said openings, 110 said tube being formed with a transverse opening and a spring disposed within said opening and bearing against said jaws adjacent their points of pivotal mounting.

9. A tweezer including a pair of jaws, a tube within which the inner ends of said jaws extend to have slidable movement, a plug within said tube, the ends of said jaws bearing loosely against said plug, means engaging said plug to normally project the same together with said jaws and a pair of arms connected to said jaws to move the same into gripping position and subsequently shift said jaws together with said plug inwardly within said tube.

10. A tweezer including a pair of jaws, a tube, a plug slidably mounted within said tube and presenting a squared portion, the inner ends of said jaws being similarly shaped and bearing loosely against the side walls of said squared portion and interposed between the same and the inner face of said tube, means bearing against said plug for normally projecting the same together with said jaws and a pair of arms connected to said jaws to move the same to gripping position and subsequently bodily retract the same.

11. A tweezer including a tube, a pair of jaws, the inner ends thereof extending slidably within said tube, a pair of arms rockingly mounted upon said tube, a spring interposed between said arms and extending through a bore formed transversely of the tube body and means for connecting said arms to said jaws to bring the same into gripping position and subsequently retract said arms.

In testimony whereof I affix my signature.
SAMUEL SEGAL.
